CORSET

Vita Buchanan, New York, N. Y.

Application June 16, 1934, Serial No. 730,862

4 Claims. (Cl. 2-37)

My invention relates to improvements in corsets and analogous garments, and the same has for its object to provide corset which will fit perfectly; be comfortable to the wearer, and which will readily conform itself to the figure of the wearer in all positions which the wearer may assume.

Further, said invention has for its object to provide a corset which will readily accommodate itself to the varying positions of the wearer, and which will at all times be maintained properly to its adjusted position, and which will not "ride" up on the person.

Further, said invention has for its object to provide a corset with means for holding the rear lower portion or seat of the garment conformed closely to the contour of the figure, which means will also serve to prevent the corset "riding" up, and serve to support the stockings upon the wearer.

Further, said invention has for its object to provide an attachment for the purposes above specified, which may be readily secured to the inner side of a corset at or adjacent its lower rear edge or seat portion, and having means for securement to the stockings whereby to duly support the same, and at the same time serve to hold the corset from "riding" up upon the person of the wearer.

Other objects will in part be obvious, and in part be pointed out hereinafter.

To the attainment of the aforesaid objects and ends my invention consists in the novel features of construction, and in the combination, connection and arrangement of parts hereinafter more fully described and then pointed out in the claims.

In the accompanying drawing—

Figure 1 is an illustrative view showing one form of corset constructed according to and embodying my invention in position upon the wearer;

Fig. 2 is a front view, slightly in perspective, showing the attachment as it appears upon the inner rear side or seat portion of the corset;

Fig. 3 is a side view thereof with the lower rear edge of the corset turned up, and

Fig. 4 is an enlarged face view of the attachment apart from a corset.

In said drawing 10 designates a corset which may be of any desired type, but is here shown as a closed front corset, corselette or girdle. The body portion may be made entirely of elastic material or fabric, or of inelastic material, or it may be made partly of elastic and partly of

inelastic materials, as desired. In the accompanying illustration I have shown the corset made of elastic material and provided upon its inner side at or near its lower rear edge, which constitutes the seat portion of the garment, with a horizontally-disposed attachment comprising a relatively narrow longitudinal member 13 formed of elastic fabric which is preferably capable of stretching or yielding in all directions, i. e. vertically, horizontally, and diagonally. The fabric has certain of its elastic threads preferably disposed transversely of the length of said member 13 so as to insure its yielding in a vertical, or more or less vertical direction. The upper edge of said member 13 is preferably straight and the lower edge rounded or curved.

The longitudinal member 13 is secured along its upper edge, and at its opposite sides for a short distance downwardly from its upper edge, to the inner side of the rear part of the corset 20 above the lower edge thereof by one or more rows of stitching 16, and has its lower edge free so as to permit of the lower rear edge of the corset which extends below the lower edge of said member 13 being turned up or raised independently of the member 13 when necessary.

The said member 13 is provided at its lower edge at or adjacent to its ends with diagonally-downwardly and forwardly-extending members or straps 15, 15 which may be made either integrally with said member 13, or separately therefrom, and secured thereto at their upper ends by sewing or other convenient means. The other or free ends of said members or straps 15 are provided with adjustable attaching devices 17 35 adapted to engage with hooks 18 at the lower edge of the corset at each side thereof. Each member or strap 15, 15 is provided intermediate its ends with a sliding or movable attaching device 19 adapted for securement to the upper outer edge 40 of a stocking.

While I have shown and described the members or straps 15, 15 as being made separate and secured to the lower edge of the member 13, it will, of course, be understood that said parts may be formed either integrally with or as parts of the member 13 and of the members 16, 16^a, or separately therefrom, and when formed separately may be made of elastic or inelastic material, as circumstances may dictate.

Further, it is to be noted that the member 13 is adapted for use in connection with corsets, corselettes and girdles, and that the same may be incorporated therewith at the time of making 55

the garment, or may be applied to a previously finished garment.

Having thus described my said invention, what I claim and desire to secure by Letters Patent is:

- 5 1. A corset or similar garment including a relatively-narrow longitudinal member secured along its upper edge to the inner side of the lower rear portion of said garment in position entirely concealed thereby and having its lower edge free, and stocking supporting members extending from said free edge.
- 10 2. A corset or similar garment including a relatively-narrow longitudinal member secured at its upper portion to the inner side of said garment adjacent the rear lower edge thereof and in position entirely concealed by the lower rear portion of the garment and having its lower portion free, and stocking supporting members extending from said free portion.
- 15 3. A corset or similar garment including a longitudinally and vertically-yielding longitudinal

member secured along its upper edge to the inner side of said garment at the seat portion thereof and in position entirely concealed thereby and having its lower portion free, and a plurality of stocking supporting members extending from the free portion of said member at points adjacent the ends thereof.

4. A corset or similar garment including a longitudinal member secured along the edges of the upper portion thereof to the inner side of said garment at the seat portion thereof in position entirely concealed thereby and having a free lower portion, and stocking supporting members extending from said lower portion for maintaining said seat portion from points inwardly of 15 and above the lower edge thereof under tension; the lower rear edge of the corset below the line along which said longitudinal member is secured to the corset being free for movement relative to the tensional lower portion of said member. 20

VITA BUCHANAN.
